UNITED STATES PATENT OFFICE

HULDA M. FELDKAMP, OF ELKHART, INDIANA

DISPLAY RACK

Application filed March 30, 1931. Serial No. 526,369.

The present invention relates to a display rack especially designed for dispensing and displaying motor oils at service stations, garages and like places where motor oil is sold.

The prime object of the invention resides in the provision of a rack of this nature wherein a light is displayed among a plurality of oil dispensing containers.

Another very important object of the invention resides in the provision of a rack of this nature which holds the dispensing receptacles firmly in place against accidental removal.

Another very important object of the invention resides in the provision of a display rack of this nature which is simple in its construction, inexpensive to manufacture, strong and durable, easy to manipulate, thoroughly efficient and reliable in use, compact and convenient in its arrangement of parts, attractive in appearance and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of a rack embodying the features of my invention.

Figure 2 is a sectional view taken substantially on the line 2—2 of Figure 1.

Figure 3 is a sectional view taken substantially on the line 3—3 of Figure 1.

Figure 4 is a vertical section taken substantially on the line 4—4 of Figure 2.

Figure 5 is a fragmentary plan view showing the containers in section taken substantially on the line 5—5 of Figure 1.

Figure 6 is a sectional view taken substantially on the line 6—6 of Figure 4.

Figure 7 is a fragmentary perspective view of one of the uprights of the frame showing the eye thereon.

Figure 8 is a fragmentary perspective view of the two frame rings with a portion of the handle structure attached thereto, and

Figure 9 is a fragmentary perspective view of a portion of the tray.

Referring to the drawings in detail it will be seen that I have devised a frame structure including an outer ring 5 and an inner ring 6 slightly spaced therefrom. Inverted U-shaped bails 7 have ends welded between portions of the rings 5 and 6 to rise therefrom and the centers of the eight portions of these bales merge into the ends of inverted U-shaped bale 9 which forms the handle.

Rods 10 depend downwardly from the outer ring 5 and slant slightly inwardly the major portion of their lengths and terminate in vertical portions 10'. At the lower ends 65 of the slanting portions of the rods 10 there are formed inwardly directed eyes 11. The portions 10' merge into outwardly radiating horizontal extensions 12 which merge into uprights 14 about the ends of which is a horizontal ring 15. A plurality of rings 16 connect the horizontal radiating extensions 12 so as to form a tray or the like in which the bottoms of oil dispensing receptacles may rest. A circular plate 17 is fixed on top of the frame 75 rings 5 and 6 and the peripheral edge thereof is formed with a plurality of notches 18. The edge portions between the notches 18 are formed with depending extensions 19.

Rods 20 are slidable through openings in 80 the plate 17 and through the eyes 11. A ring 21 connects the upper ends of these rods 20. Radial horizontal rods 22 extend from the ring 21 and terminate in depending end portions 23. Springs 24 are disposed about portions of the rods 20 and impinge upwardly against the bottom of the plate 17 and downwardly against cross pins 25 in the rods 20 so as to hold the ring 21 normally downwardly with the fingers or extensions 22 and their 85 portions 23 against oil receptacles which are resting in the tray structure thereby preventing the accidental displacement of these receptacles. To take out one of the receptacles, of course, it is only necessary to lift the same 90 against the tension of the spring 24.

An electric light socket 30 is mounted in the central opening in the plate 17 so that an electric light 31 may depend downwardly therefrom among the oil receptacles.

It is thought that the construction, utility and advantages of this invention will now be quite apparent to those skilled in this art without a more detailed description thereof.

5 The present embodiment of the invention has been described in considerable detail merely for the purposes of exemplification since in actual practice it attains the features of advantage enumerated as desirable in the 10 statement of the invention and the above description.

It will be apparent that changes in the details of construction, and in the combination and arrangement of parts may be resorted to 15 without departing from the spirit or scope of the invention as hereinafter claimed or sacrificing any of its advantages.

Having thus described my invention, what I claim as new is:

20 1. A rack structure of the class described including a ring, rods depending from the ring, an annular tray mounted about the lower ends of the rods, a plate on the ring, rods 25 slidable through openings in the plate within the ring, spring pressed means for urging the second mentioned rods downwardly, and means on the rod above the plate for holding receptacles in the tray against accidental displacement.

30 2. A rack structure of the class described including a ring, rods depending from the ring, an annular tray mounted about the lower ends of the rods, a plate on the ring, rods 35 slidable through openings in the plate within the ring, spring pressed means for urging the second mentioned rods downwardly, a ring formed on the upper ends of the second mentioned rods and having outwardly 40 radiating fingers extending therefrom terminating in downwardly disposed extensions.

3. A rack structure of the class described including a ring, rods depending from the ring, an annular tray mounted about the lower ends of the rods, a plate on the ring, rods 45 slidable through openings in the plate within the ring, spring pressed means for urging the second mentioned rods downwardly, a ring formed on the upper ends of the second mentioned rods and having outwardly 50 radiating fingers extending therefrom terminating in downwardly disposed extensions, said plate being formed at its edge with peripheral notches one between each 55 pair of depending extensions of said fingers.

4. A rack structure of the class described including a ring, rods depending from the ring, an annular tray mounted about the lower ends of the rods, a plate on the ring, rods 60 slidable through openings in the plate within the ring, spring pressed means for urging the second mentioned rods downwardly, a ring formed on the upper ends of the second mentioned rods and having outwardly 65 radiating fingers extending therefrom ter-

minating in downwardly disposed extensions, said plate being formed at its edge with peripheral notches one between each pair of depending extensions of said fingers, the first mentioned rods being formed adjacent their lower ends with inwardly directed eyes through which the bottom end portions of the second mentioned rods are slid able.

In testimony whereof I affix my signature.

HULDA M. FELDKAMP.
